Fig. 4

Fig. 3

FIG. 1 is a view in perspective of a hair-curler showing my new design.

FIG. 2 is a longitudinal view thereof.

FIG. 3 is an end view thereof.

FIG. 4 is an end view thereof taken from the opposite direction.

The characteristic features of my design reside in the combination of a cylindrical straight sided roller body having a plurality of projections extending from the roller surface, the projections being of successively differing heights and arranged to define a concave area centrally of the roller, and the projections further being arranged in groups of rows and the longitudinal axes of the projections in each group being parallel with respect to each other.

I claim:

The ornamental design for a hair-curler, substantially as shown and described.
